UNITED STATES PATENT OFFICE.

REUBEN C. BAKER, OF COALINGA, CALIFORNIA.

ANCHOR FOR WELL-TUBING.

1,023,292.

Specification of Letters Patent.

Patented Apr. 16, 1912.

Application filed November 6, 1911. Serial No. 658,777.

To all whom it may concern:

Be it known that I, REUBEN C. BAKER, a citizen of the United States, residing at Coalinga, in the county of Fresno and State 5 of California, have invented a new and useful Anchor for Well-Tubing, of which the following is a specification.

This invention relates to anchors for use in connection with tubes in deep wells.

10 Where oil or the like is to be pumped from wells of considerable depth, it has been necessary heretofore to place in the well casing a tube having a pump on the bottom end thereof, the sucker rods being arranged 15 within this tubing so as to work the valves in the pump. Where this arrangement of parts is employed the tubing is suspended from the top of the casing and entirely unsupported at the bottom end of the pump. 20 As a result, the tubing often becomes broken and thus permits the lower part thereof to drop to the bottom of the well, thus necessitating a very costly operation of lifting out the broken parts.

25 One object of the present invention is to provide means, at the pump end of the tubing whereby, should the tubing become broken, the lower portion thereof will be immovably anchored within the casing and 30 thus prevented from dropping to the bottom of the well.

Another object is to provide means whereby the gripping elements of the anchor are automatically actuated should the tubing 35 part before all parts of the structure have been assembled.

With the foregoing and other objects in view which will appear as the description proceeds, the invention resides in the combination and arrangement of parts and in the details of construction hereinafter described and claimed, it being understood 40 that changes in the precise embodiment of the invention herein disclosed can be made 45 within the scope of what is claimed, without departing from the spirit of the invention.

In the accompanying drawings the preferred form of the invention has been 50 shown.

In said drawings:—Figure 1 is a central longitudinal section through the upper portion of the anchor within a well casing, the pipe of the standing valve being indicated 55 by dotted lines. Fig. 1^a is a view of the lower portion of the anchor. Fig. 2 is a

section on line X—X Fig. 1. Fig. 3 is a section on line Y—Y Fig. 1^a.

Referring to the figures by characters of reference 1 designates the upper tubular section of the anchor, the upper end of said section being reduced, as at 2, and being exteriorly screw threaded for engagement with the coupling 3 in which is formed a seat 4 for the standing valve commonly used. The lower tubular section 5 of the anchor has a ring 6 secured on to the lower end thereof and the two sections 1 and 5 are connected by a coupling ring 7 tapered downwardly so as to constitute a wedge for 70 the purpose hereinafter set forth. Spring strips 8 are secured at their upper ends to the inner face of the coupling ring 7 at points between the sections 1 and 5 and these strips converge downwardly and terminate, 75 at their lower ends, in ears 9 to which are riveted or otherwise fastened shoes 10 carrying antifriction rollers 11. These shoes are mounted to slide within openings 12 formed within the section 5 at diametrically opposed points.

A collar 13 extends around the lower portion of the section 5 and normally rests on the upper face of the ring 6. Spring strips 14 extend into and are secured to this collar and are adapted to slide along the outer surface of the section 5, the two spring strips 14 being located at diametrically opposed points. The upper end portions of the strips 14 diverge upwardly and are secured to gripping shoes 15 contacting loosely with the wedging or coupling ring 7, the outer or working faces of these shoes being toothed, as indicated at 16. Under normal conditions the shoes 15 are in contact with the lower end portion of the coupling 7 and the shoes 10 are held retracted into the section 5 by the strips 14, as shown in Fig. 1.

100 Longitudinal slots 17 are formed within the lower portion of the section 5 at diametrically opposed points and receive the end portions of a pivot rod 18 the terminals of which are secured to the collar 13. A disk 19 is pivotally mounted on the rod 18 at a point off center and normally bears against a stop 20 extending inwardly from the wall of the section 5, said stop being preferably in the form of a pin seated at one end within the wall. The stop is of such length as to hold the disk normally 110 inclined, as shown in Fig. 1^a. A stop pin 21 extends from one of the strips 14 and

through a longitudinal slot 22 in casing section 5, this pin being adapted to limit the upward swinging movement of the lower end portion of disk 19, the disk, upon contacting with this stop pin, assuming the position shown in dotted lines in Fig. 1^a.

In using the present invention, the anchor is coupled to the bottom of the pump and the tubing is then lowered into the well casing A. Should the tubing part or break during this portion of the operation, the disk 18, upon striking the surface of the fluid in the well, will be swung to the position indicated in dotted lines in Fig. 1^a, thus causing relative movement of the collar 13 and the casing section 5. The strips 14, which move with the collar 13, will support the shoes 15 in position where they will be promptly spread apart by the collar 7 so as to bring the toothed face 16 of each shoe in engagement with the inner surface of the casing A. The parts will thus be held automatically and can be easily reached for the purpose of raising them from the well.

If the tubing should not part or break, it will be lowered into the casing A until the pump has been brought to the desired depth. The pump valves are then put in fast to the sucker rods. The bottom of the standing valve of every pump of this type is tapped to receive a section of pipe. This pipe section, which has been indicated by dotted lines at B is utilized in the present structure for the purpose of actuating the gripping shoes 15 under certain conditions. After the standing valve has been positioned at the bottom of the pump the pipe B will extend down into the anchor and shift the strips 8 so as to force the shoes 15 into engagement with the casing. Thus it will be seen that should the tubing part or break the teeth on the shoes 15 will prevent any of the structure from dropping to the bottom of the well.

What is claimed is:—

1. A tubing anchor including upper and lower sections, a tapered coupling therebetween, downwardly converging spring strips secured to the coupling and projecting into the lower section, shoes carried by said strips and mounted within openings in the lower section, spring strips mounted upon the outer face of the lower section and adapted to be shifted outwardly by the shoes, and casing gripping elements carried by said strips, said elements being movable longitudinally of the section and against the coupling, said coupling constituting means for shifting the shoes radially during such movement.

2. A tubing anchor for attachment to a

pump, including a tubular portion, spring elements mounted upon the outer face of said portion, gripping devices carried by the free ends of said elements, downwardly converging resilient devices within the tubular portion, and means carried thereby and movable through said tubular portion to engage the spring elements.

3. A tubing anchor including a tubular portion, means mounted for movement longitudinally therein under the force of the impact of a fluid thereagainst, casing gripping elements shiftable with said means, and means carried by said tubular portion for shifting said elements radially in opposite directions and into engagement with the casing during such longitudinal movement.

4. A tubing anchor including casing gripping elements shiftable radially, a spreading element, and means operated by impact upon fluid in the casing during the downward movement of the anchor and cooperating with said spreading element, for shifting said gripping elements into engagement with the casing.

5. A tubing anchor including casing gripping elements shiftable radially, a normally inclined flap pivotally mounted and shiftable longitudinally of the anchor, connections between the flap and the gripping elements, and means co-operating with said elements for shifting them radially during the movement of the flap relative to the anchor.

6. A tubing anchor including upper and lower sections, a coupling therebetween, downwardly converging spring strips secured to the coupling and projecting into the lower section, shoes carried by said strips and mounted within openings in the lower section, spring strips mounted upon the outer face of the lower section and adapted to be actuated by the shoes, and casing gripping elements carried by said strips.

7. A tubing anchor including upper and lower sections, a tapered coupling ring connecting the sections, a flap pivotally and slidably mounted within the lower section, a collar extending around said section and movable with said flap, and yieldingly supported gripping elements movable with the collar and shiftable against the coupling ring, said ring constituting means for shifting said elements laterally into engagement with the inner wall of the well casing.

In testimony that I claim the foregoing as my own, I have hereto affixed my signature in the presence of two witnesses.

REUBEN C. BAKER.
